UNITED STATES PATENT OFFICE.

ARNOLD J. WEST, OF ABERDEEN, WASHINGTON TERRITORY.

INDICATOR FOR SAW-MILL SET-WORKS.

SPECIFICATION forming part of Letters Patent No. 325,295, dated September 1, 1885.

Application filed March 23, 1885. (No model.)

To all whom it may concern:

Be it known that I, ARNOLD J. WEST, a citizen of the United States, residing at Aberdeen, in the county of Chehalis and Territory 5 of Washington, have invented a new and useful Improvement in Indicators, of which the following is a specification, reference being had to the accompanying drawings.

My invention relates to an improvement in 10 indicators for saw-mills; and it consists in the peculiar construction and combination of parts, that will be more fully set forth herein-after.

In the accompanying drawings, Figure 1 is 15 a perspective view of an indicator embodying my invention. Fig. 2 is a top plan view of the same.

A represents a way in which the head-block B travels back and forth. Projecting from 20 one side of the way, at the rear end thereof, is an indicator or hand, C. A shaft, D, is journaled in rear of the way A, and to this shaft is fixed a drum, E. Around the shaft D, on one side of the drum, is wrapped a spring, F, 25 which has one end fixed to the drum and its opposite end fixed as at f. To the periphery of the drum is secured the rear end of a band, G, the front end of which band is secured to a lug, b, that projects from one side of the head-block. The indicator C extends across the 30 upper face of the band. This band is provided on its upper face with a graduated scale, formed in columns that run parallel to the length of the band. The column to the left is divided into inches. To the right of the 35 inch-column is a column that is graduated to indicate inch-boards, then a column graduated to indicate two-inch boards, and so on to indicate any desired thickness.

40 As the head-block is moved forward the band uncoils from the drum, and as the head-block is moved rearwardly the spring F ro-

tates the drum and winds the band upon it. As the band moves under the stationary hand the operator can see at a glance the number 45 of inches from the standard to the saw, and can tell how many boards of a given thickness the piece of timber he is sawing will make.

If it is desired to saw inch-boards, the operator sets the head-block up for the first slab until the hand comes even with the end of the column indicating inch-boards.

This device will also indicate where to set the head-block for the first slab when it is desired to saw inch-boards, after having previously sawed boards of greater thickness, in order to make the slabs come out even, and thus avoid waste.

An indicator thus constructed is cheap and 60 simple, and is thoroughly reliable and efficient in operation.

Having thus described my invention, I claim—

1. The combination of the head-block, the 65 stationary indicator-hand secured to the way in which the head-block travels, and the graduated band that moves back and forth with the head-block, substantially as described.

2. The combination of the head-block, the stationary indicator-hand, the graduated band connected to the movable head-block, the drum to which the rear end of the band is secured, and the spring for turning the drum 75 and winding the band when the head-block is retracted, substantially as described.

In testimony that I claim the foregoing as my own I have hereto affixed my signature in presence of two witnesses.

ARNOLD J. WEST.
